UNITED STATES PATENT OFFICE

155,381

DESIGN FOR A COMBINED SHIRT AND TIE

Virgil Black, Grand Ridge, Ill.

Application April 5, 1948, Serial No. 145,529

Term of patent 14 years

(Cl. D3—25)

To all whom it may concern:

Be it known that I, Virgil Black, a citizen of the United States of America, residing at Grand Ridge, in the county of La Salle and State of Illinois, have invented a new, original, and ornamental Design for a Combined Shirt and Tie, of which the following is a specification, reference being had to the accompanying drawing, forming a part thereof, wherein:

Fig. 1 is a front view of a combined shirt and tie showing my new design.

Fig. 2 is a fragmentary front view of the shirt in closed position.

Fig. 3 is a view similar to Fig. 2 illustrating the shirt in an open position.

The back of the shirt is conventional and the essential features reside in the portions shown in full lines on the drawing.

I claim:

The ornamental design for a combined shirt and tie, as shown and described.

VIRGIL BLACK.
